ABSTRACT OF THE DISCLOSURE

A copying apparatus having a slot shaped exposure orifice parallel to and adjacent to a narrow edge of a substantially rectangular frame. Transport rollers protrude above the top cover of the apparatus and cooperate with a transparent, plate-shaped carrier for the original. Charging and exposure components are provided for producing an image on an electrophotographic band. The image is then transferred to the final support which may be of any desired material.

Known copying devices of the kind hereinbefore mentioned may comprise, in the zone of the exposure orifice, a removable frame, for example, with contact pressure rollers, which engage with the transport means and whereby the foliate original may be passed without a plate-shaped carrier. In such a construction, described in U.S. Pat. No. 3,510,218, May 5, 1970, the plate-shaped carrier is used for copying thicker originals, e.g., books, in that the carrier is pressed by the transport means against the original. This construction is included in the present invention.

The exposure device with a slot-shaped exposure orifice at one top edge of the apparatus makes it possible to construct an apparatus of small dimensions, because the exposure may be made directly on an electrophotographic receiving material on an L-shaped exposure travel. The receiving material passes the exposure device along a rectilinear path so that the exposure is made in strips.

This proposed construction necessitates the use of an electrophotographic receiving material and prevents copying on letterheads or the like.

It is also known, for example from U.S. Pat. No. 2,357,809, to use a roller-shaped carrier with a possibly intermittent coating of a photoconducting insulating material as recording carrier, on which the original is exposed and on which a powder picture is developed, which is then transferred by contact pressure to an ordinary piece of paper. This known device required the use of a transparent original, exposed by transillumination exposure if it is passed directly along the cylinder with the electrophotographic exposure carrier. Hence, the usability of this apparatus is rather limited.

In addition, there are also known electrophotographic copying apparatus, having a selenium drum as recording carrier, on which an original is exposed which is placed flatly on a picture platform. The exposure devices required for this purpose are fairly complicated because they have to move under the picture platform in synchronism with the drive of the selenium drum for scanning the original in strips so that the strips may be reproduced on the surface of the drum with sufficient clarity. These known copiers are therefore very large and require a high expenditure of guide and control means, already in the zone of the exposure section. In addition, the operation is fairly complicated where foliate originals are used, which must always be placed flat on the platform, and must be covered and adapted. In addition, there are various restriction with regard to size, because originals larger than the platform cannot be copied.

2

It is an object of the invention to improve the proposed apparatus so that any desired foliate material may be used as receptor material.

In this, the invention is based on a construction which comprises a slotted exposure orifice parallel to and adjacent to a narrow edge of the substantially rectangular upper surface of the apparatus and the said transport means on or above the top surface of the apparatus, preferably in conjunction with the said frame with contact pressure rollers and with a transparent, plate-shaped carrier for the original.

It is another object of the invention to provide an apparatus of this kind, characterized by a particularly favourable construction with regard to the distribution of heat and the arrangement of the heat sources within the apparatus.

It is a further object of the invention to provide an apparatus in which a band-like recording carrier is so guided that contamination of the apparatus by the injection of powder is prevented.

It is a further object of the invention to provide an apparatus of small dimensions permitting the production of copies of widely varying originals without any extensive re-registration.

According to the invention, these objects are realized in the electrophotographic recording carrier is reversed and driven synchronously to the said transport means in the zone of the exposure device, at least between the charging device and the picture transfer section; that the exposure device has two picture beam deflecting devices, such as mirrors which produce an inverted image on the recording carrier; and that a known picture transfer device is provided on the electrophotographic recording carrier which receives foliate receptor material from the stack; this receptor material may be ordinary, that is to say, otherwise not prepared, paper.

The combination of a slotted exposure orifice, over which the original is guided on the upper side of the apparatus, with a deflected recording carrier which has, in a preferred embodiment of the invention a circular curvature, represents a particularly advantageous solution, because the original is here scanned in strips without requiring therefor special carriers in the apparatus within the zone of the exposure device.

In a preferred embodiment of the invention, the electrophotographic recording carrier is endless and passes with its section alongside the charging device and the picture transfer device; between these stations and behind the picture transfer device, there are cleaning means for cleaning the carrier prior to a new exposure. Obviously, this exposure carrier will have the form of an endless band. This permits a comparatively flat construction of the apparatus, if the band has a larger component parallel to the top surface of the apparatus.

In another preferred embodiment of the invention, a band-like recording carrier is guided over a cylinder in the zone of an inner picture section of the exposure device. This band-shaped carrier may be dimensioned for a certain number of copies of a certain size and is then changed, or, if associated with the said cleaning means, fitted in reverse by fitting the storage reel instead of the take-up reel, which now acts as storage reel.

Also this construction makes possible a very flat design with the additional advantage that the picture beam extends between the deflecting devices immediately below the top surface of the apparatus from the exposure orifice located at one edge. This construction shows that the combination of a slot-like exposure orifice on the top of the apparatus with an exposure material guided in the apparatus along a circular, curved path, brings about a surprising simplification in the construction of the exposure device.

Preferably, a powder applicator is located at the edge remote from the exposure orifice and is accessible from this edge through a cover, in order to supply the powder. In this manner, the developing powder is provided at a point remote from the exposure and the risk of contamination is reduced.

It is also preferred that the space with the recording carrier should be closed by partitions to form a chamber, having merely apertures for passing the recording carrier and for the exposure, wherein the recording carrier takes the applied powder away from the adjacent partition in the zone under the powder applicator, the delivery orifice of which is lower than the exposure position. Also this solution is made possible by the said arrangement of the powder applicator and by the essential, circularly curved guide of the recording carrier in the zone of the exposure device. This arrangement prevents contamination in the zone of the exposure of the original on to the exposure carrier, which might occur if a rectilinear guide were used for the recording carrier along the exposure device and powder applicator.

Preferably, the stack for the foliate receptor material is arranged in a shelf above the base of the apparatus and a U-shaped guide is provided on the recording carrier in conjunction with the withdrawing means, wherein the picture transfer has contact pressure rollers and the recording carrier a delivery mechanism downstream thereof, in order to detach the receptor material after the picture transfer. Such a detaching mechanism may be a stripper, and may operate with pneumatic or mechanical suction devices cooperating only with the reverse side of the receptor material. However, it is also possible to provide a blowing device which operates against the leading edge of the receptor material; in this case, there is preferably provided a deflection about a roller with comparatively small diameter, where a band-like recording material is used. Such a roller, or else a strip about which the recording material is pulled at an angle, may also be sufficient as only means. Under the action of such a deflection, the receptor material becomes automatically detached.

Such removing devices are known in the art.

According to a further feature of the invention, a burner chamber is arranged substantially at mid-height of the apparatus, adjacent to the chamber for the recording carrier and substantially underneath the exposure slot; the heat sources of this burner are directed downwardly towards a guide for the receptor material to a delivery orifice, and this burner chamber contains also a fan for removing the excess heat above the heat sources and from the light sources provided in the zone of the exposure slot. Since the thermal parts are arranged on one side of the housing, a particularly effective ventilation is possible. These parts, releasing heat are primarily the heat sources and the exposure light sources, between which extends the so-called burner chamber. The main drive motor may also be arranged within the zone of this burner chamber.

If a band-like recording carrier with storage and take-up reels is used, the chamber for the recording carrier is divided, according to a preferred embodiment of the invention, by a partition having a passage, and separating a sub-chamber with the storage reel, the charging device and the picture transfer section from another sub-chamber, containing the take-up reel and the cleaning device, mounted above a removable collecting trough.

The invention will be further described, by way of example, with reference to the accompanying drawings, showing an embodiment thereof, and in which:

FIG. 1 is a side elevation of a device according to the invention in cross-section along a plane parallel to the plane of the drawing, the parts being shown in their diagrammatical association;

FIG. 2 shows a detail of FIG. 1, explanatory of a special embodiment;

FIG. 3 shows diagrammatically the drive units in connection with a control; and

FIG. 4 is a side elevation with elements according to FIG. 1, explanatory of another embodiment of the invention.

A box-shaped housing has a base 1 and a top wall 2, forming the upper side of the apparatus, these walls being connected by side walls, of which the side walls 3 and 4 are shown, whilst the remaining two extend parallel to the plane of the drawing. The top of the apparatus is substantially rectangular. Near the edge 64 of the side wall 4 is a slot-shaped or strip-shaped exposure orifice 5, extending parallel to the side wall 4; this orifice may be covered by a transparent cover 6. In front of and behind the exposure orifice 6, the upper surface of the apparatus has perforations 7, 8, 9, 10, through which extend sections of transport means, in this case of rollers 11, 12, 13, 14, which extend upwardly. The said rollers 11 through 14 are driven in the direction of the arrow 15, shown in roller 11.

A detachable frame 16 is arranged over the top surface 20 of the apparatus in the zone of the exposure orifice 5 and the rollers 11 through 14. This frame carries counter-pressure rollers 17, 18, 19, 20, associated substantially with the rollers 11 through 14, resiliently urged thereagainst by spring pressure, and being, for example, freely rotatable. When a foliate original is introduced through an insertion slot 21 on the edge of the frame facing the center of the apparatus, these rollers transport the original foliate sheet past the exposure orifice 5 to a delivery slot 22.

Adjacent to the frame 16, a transparent plate 23 of glass, plastic or the like is placed on the upper surface of the apparatus. The length of this plate corresponds to that of the original which is usually to be processed in the apparatus. However, it should be noted here that foliate originals of practically any length can be passed under the frame 16, if receptor materials of suitable length are used or if the withdrawing means are so arranged that they apply the foliate receptor sheets immediately successively from a stack.

The plate 23 forms a carrier, for example for book-shaped originals. The plate may be guided on the top of the apparatus for movement parallel to the plane of the drawing, the guide means may be a web 105 arranged on one long side of the top cover 2 and engaging into a complementary, downwardly open groove in the plate 23. 45 When the frame 16 with the contact pressure rollers 17 through 20 is lifted, for example raised, the plate 23 may be guided by the transport rollers 11 through 14 and its velocity is controlled by the rotational speed of the rollers 11 through 14.

50 The frame 16 is connected detachably with the main housing by means of hinges 118, 119.

A construction of the type hereinbefore described has been disclosed in the above mentioned Pat. No. 3,510,218, May 5, 1970.

55 Exposure light sources 24, 25 in reflectors are provided on the edges of the exposure orifice 5 and illuminate an original guided through the exposure orifice. The exposure device may have light deflecting devices 26, 27, for example mirrors or prisms which are so arranged that the 60 picture beam 28 extending between them and the zone of which may comprise a system of lenses 29, extends parallel to the upper surface 2 of the apparatus and immediately underneath the same. Partitions 30, 31, arranged on the side walls extending parallel to the plane of the drawing, embrace the picture beam and prevent dust from other parts of the apparatus from entering.

In the embodiment shown, there is under the deflecting device 27, a cylinder 32 over which a band-like recording carrier 33 passes from a storage reel 34 to a take-up reel 35. In the path of the recording carrier, transport, rollers 36, 37, driven for example in the sense of the arrows shown, are arranged in front of a charging device 38. These rollers may have a metal surface or an insulating shell with a metal core, and connected in a certain manner to a voltage. The charging device may have a conventional

construction, for example, with two corona wires 106 through 109 above and below the recording carrier 33. This charging device is associated with a known high voltage supply, not shown in detail in FIG. 1.

Behind the cylinder 32, which consists preferably of insulating material, the recording carrier is guided obliquely downwardly to a deflecting roller 39 and from there to a transfer device, shown generally at 40. The obliquely downwardly directed run between the cylinder 32 and the roller 39 is regarded as essential. The substantially horizontal run between the roller 39 and the transfer device 40 is desirable, because in this zone the adhering powder of a powder picture is no longer exposed to side forces, and loose powder drops off without imparting parts of the picture.

The transfer device 40 consists in this embodiment of a cylinder 41 and two transport rollers 42, 43, running on the circumference of the cylinder. The receptor sheet is applied in this zone, by means to be described further below. The transfer of powder taking place here may be affected by the application of an electric voltage by means of a recharging device 44. The recharging device 44 may have, for example, electrode wires 110, 111, affected by a certain potential, for example, a pulsating voltage. The cylinder 41 may have a metal core or shell, acting as a second electrode.

From the transport roller 42, the recording carrier passes to the take-up reel 35. The latter may be provided, for example, with brushing roller 45, 46, for removing powder residues, which may drop into a trough 47, arranged in this location, from where they are returned at intervals to the powder storage supply.

It is also possible to provide a powder suction device as at 48.

In connection with the partition 31, and by means of further partitions 49, 50, 51, a substantially closed chamber is formed for the recording material. The partition 51 has a hole 52 for the passage of the recording material, and a cylinder 32 may be arranged in this hole. In addition, a further aperture 53 is provided for introducing the said recording material into the chamber.

The partition 50 terminates at 54 in front of the transfer device 40. The aperture formed in this manner is only as wide as the recording carrier, and this also applies to the remaining apertures; consequently, the chamber for the recording carrier is closed by the carrier itself. The drawing also shows diagrammatically at 54 a stripper 55 for the receiving material, but this may have any other construction, comprising, for example, suction cups or the like.

In the embodiment shown, comprising a band-like recording carrier operated with a storage and a take-up reel, the chamber just described is divided by a further partition 56 with an aperture 57, adapted to permit the recording carrier to pass therethrough. In this manner, the excess of powder, may, for example by means of the brushing rollers 45, 46, be removed in a separate chamber without the risk of dusting the recording carrier before the exposure of a picture thereon.

Under the top or cover plate 2, and near the edge 58 remote from the edge 64, there is a storage tank 59 for the developer powder. This storage tank is accessible from the top via a flap 79, mounted, for example, at the end of the top cover 2. This tank tapers towards the bottom after the manner of a funnel, the oblique wall portion 60 defining, in conjunction with other wall portion 112 a delivery orifice 61, located preferably within the range of the cylinder 32 immediately above the recording carrier 33, but, as viewed in the direction of rotation, at a point below the apex of the cylinder 32, where the exposure is made. In this way, the developing powder can continuously drop on the oblique section of the recording material between the cylinder 32 and the roller 39 and may run over this section into the funnel-shaped, tapering, lower part 62 of this part of the housing. Between this lower part 62, act-

ing as collecting chamber, or the lowest part of this section, and the storage tank 60, there may be a bucket elevator-like, known, lifting and transport mechanism 63 which returns the collected powder back to the storage tank 59.

Above the base 1, and accessible through a closable opening at 65, there is a shelf-like, withdrawable, stack holder 66 with a stack of copying sheets. The inner end of the said stack is associated with withdrawing means, shown generally at 67, adapted to transport on actuation always one sheet in a certain manner to the transfer means. This arrangement may also comprise a control with a so-called switching roller, such as described, for example, in patent application Ser. No. 726,638. However, other means may be provided for the timed withdrawal of sheets from the stack. All these means comprise a withdrawing roller 68, running on the top sheet of the stack, followed by transport means 69, usually in the form of a pair of rollers which move the sheet into a guide. In the embodiment shown in the drawing, this guide comprises a U-shaped, upwardly bent guide member 70, guiding the sheet against the recording material in the zone of the transfer device between the cylinder 41 and the roller 43.

Adjacent to the transfer device, there is arranged a horizontal partition 72, leading to a delivery orifice 71 in the side wall 4, with two transport rollers 73, 74 running, for example above or on the said partition, as indicated by the arrows, in order to transport the receptor material to the delivery slot 71.

Above this guide and in a zone adjacent to the chamber, defined at this end by the partition 49, there are provided underneath the light sources 24, 25, heat sources 75, 76 in the form of heat radiators, serving to fix or to burn in the powder picture. The space between the side wall 4 and the partition 49 forms a so-called burning chamber 77, which contains a fan, shown diagrammatically at 78. Venting slots, not shown in detail and arranged particularly in the side walls extending parallel to the exposure device, make possible the simultaneous cooling of the exposure light sources 25 and 24 and of the heat sources 75 and 76. Due to the arrangement of both these devices giving up heat on one side of the apparatus, a particularly efficient removal of excess heat is possible, with the further advantage that both heat sources are mounted at maximum possible distance from the store of powder developer.

The apparatus may be controlled, for example, by stop switches 80, 81, arranged behind the exposure slot, and actuated by the original or its carrier. A further switch 50 may be located at 82 at the withdrawing means 67 for controlling the drive of the withdrawing means in a certain manner.

Drive and control are shown diagrammatically in FIG. 3. It should be noted in this context that the driven parts 55 are actuated in the sense indicated by arrows by means of layshafts or the like from a main motor. Slipping clutches may be mounted between the storage roller 35 and the take-up reel 34, as at 113, 114, to tension the recording carrier.

As shown in FIG. 3, the apparatus comprises a main motor 115 adapted to be switched by a main switch 116. The main motor drives a gearing 83, arranged parallel to the side wall extending parallel to the plane of the drawing.

The transmission means which may also be, for example, chain or belt drives, are connected to the parts described above in the following manner.

One take-off run 84 is connected to the transport rollers 11 through 14, another take-off run 85 to the transport rollers 73, 74. These rollers may revolve after the switching on.

Another take-off run 85 is connected, via an engageable coupling 87, to a transmission 88 with the parts guiding the recording carrier 33, i.e., with the parts 34, 36, 32, 39, 40, 35 and with the transport mechanism 63, wherein in-

dividual components, for example, the transfer device 40, may have separate drives which are adapted to be correspondingly switched.

A further take-off run 89 is connected via a coupling 90 and serves as drive for the withdrawing means 67, shown merely diagrammatically.

Yet another take-off run 91 is connected by a further coupling 92, for example, to a switching roller which effects the control.

The coupling 92 for the switching roller is engaged as a function of the operation of a switch 80, 81 (see also FIG. 1), and remains engaged so long as an original is applied to the exposure slot and passes across the same. At the correct timing, the switching roller engages through a link 95 the coupling 90 and through a link 94 the coupling 87, in order to control the synchronization of the part. A further link 96 switches through the switching roller also the exposure light sources 24 and 25 for making the exposure.

Obviously, the take-off run 91 has a speed adapted to the construction of the switching roller. The control link 97 for actuating the coupling 92 contains special equipment 117, whereby the switching roller is automatically driven until it returns into a starting position after a copy has been passed through the apparatus. It must here be noted that the switching roller controls particularly the matched start of the operation of various devices, whilst the disengagement of the couplings 87, 90, 92 and the interruption of the exposure take place as a direct function of the opening of the two switches 80, 81, as indicated by the acting link 98.

It is obvious from the preceding description that the take-off runs 84, 86 are so constructed in conjunction with the transmission 83, 88 that the connected parts are synchronized.

FIG. 3 also shows that the electrical lead 120 has, behind the main switch 116, a branch 121, leading to a switch 122 and connected to the heat sources 75, 76, the corona device 38 and the re-charging device 44. The said switch 122 is switched through the connection 94 and more particularly through an actuator 123 for the coupling 87 when the switches 80, 81 are operated, and the special devices 117 may also be used directly for actuating the switch 122. Obviously, also the light sources 24, 25 may be connected to this branch of the circuit. The said switch 82 may be specifically provided for releasing the transfer device 44, when receptor material is applied thereto. With direct actuation through switches 81, 82 or the device 123, a timing member is provided for delayed de-energization.

FIG. 2 shows a detail of FIG. 1, namely the run of the band-like recording carrier 33 between the transfer device and the take-up reel 35, and particularly in the zone of the delivery or withdrawing mechanism for the receptor material. The stripper 55 shown in FIG. 1 may be omitted in the construction of FIG. 2, in that the band-like recording carrier 33 is deflected, for example, around a roller 99 with very small radius of curvature, practically at a right angle. Then the recording carrier 33 may pass over a second roller 100 into the direction leading to the take-up reel 35. The rotatable roller 99 may also be replaced by a bar. It should be noted that the powder picture transfer has already been effected at this point and that, consequently, frictional effects acting on the recording carrier are of minor importance. The solution shown in FIG. 2 has the advantage that the receptor material need not be contacted at all by mechanical means and is lifted off the recording carrier during its advance automatically by virtue of its inherent stiffness.

It should be noted that the parts mentioned in the foregoing description, such as rollers, wall portions, partitions and processing devices, shown at 11 through 14, 32, 34 through 46, 49 through 51, 56, 60, 67, 70, 73 through 76 and 78, are mounted on side walls or partitions, extending parallel to the plane of the drawing, by means

well known in the art, whilst transmission means, gearings and control members, as well as electrical devices may be mounted in a chamber arranged on this side wall, and into which extend connecting elements, roller spindles and the like.

FIG. 4 shows a special modification in which parts corresponding to those of FIG. 1 are designated by the same reference numerals. The spatial arrangement is here such that the devices shown in FIG. 1 may be accommodated.

10 In this construction, there is only an additional aperture 124 in the partition 56 of FIG. 1 in order to feed in the upper section of the band-like recording carrier 125 to the pair of rollers 36, 37. The storage roller of FIG. 1 has been replaced in this modification by a drive roller 129 which carries the endless recording carrier. It is thereby applied, by rollers 127, 129, mounted on opposite sides of the recording carrier, and of which the latter roller 129 corresponds to the take-up roller 34 of FIG. 1, to the pair of rollers 36, 37 and to the charging device 38 so that it runs, in this section, in the same way as the recording carrier 33 runs in FIG. 1.

20 The cylinder 32 of FIG. 1 has been replaced, in FIG. 4, by a curved guide 128, over which the recording carrier moves with sliding motion and on which the exposure is effected at the apex point whilst the powder is applied thereto on the sloping downward run.

25 With regard to FIG. 1, the parts 34, 36, 32, 39, 40, 35 serve as guide for the recording carrier, and in FIG. 4 this task is performed by the parts 126 through 129, 36, 39, 40.

30 I claim:

1. An improved copying apparatus comprising a housing having a transparent plate (6) mounted in the top wall and covering an exposure aperture (5); transport means (11-14) (17-20) mounted in the housing before and behind the said plate (6) and arranged for guiding an original over said plate; an exposure device extending from the exposure aperture (5) to an exposure position on a guide (32) (128) for an electrophotographic material acting as a recording carrier (33, 125), said exposure device including light sources (24, 25) and beam-deflecting elements (26, 27), whereby a reverse picture of the original is produced on the said recording carrier, a first beam-deflecting element (26) being mounted below the transparent plate (6) and deflecting the picture beam (28) under the said plate and to a second beam-deflecting element (27) which deflects the picture beam to the said exposure position; a stack device (66, 67) for a receptor material; a picture-transfer device (40) over which the recording carrier passes; transport means between the stack device (66) and the picture-transfer device (40); drive means operating said transport means to supply receptor material to the recording carrier (33, 125) in a rhythm synchronized with the exposure; a charging device (38) positioned ahead of the said guide (32) and through which the recording carrier passes; partitions (31, 49, 50, 51) forming a chamber within the said housing; an inlet aperture (53) and an outlet aperture (52) formed in one of the said partitions (51), said recording carrier passing into and out of the said chamber through the respective inlet and outlet apertures; a powder applicator (59, 60) having a delivery orifice (61) positioned to apply powder to the recording carrier at a point lower than the said exposure position on the guide (32); and drive means for moving the recording carrier through the charging device (38) over the guide (32) and through the picture-transfer device (40).

2. An apparatus as set forth in claim 1, wherein the recording carrier is guided under the delivery slot (61) obliquely downwardly to a roller (39) arranged within the housing, and from there substantially horizontally to the transfer device (40).

3. An apparatus as set forth in claim 1, wherein the exposure aperture (5) is located at one edge of a cover plate (2) for the housing; wherein the said powder appli-

cator (59-60) is arranged under the opposite edge of the cover plate; and including a cover (79) closing the powder applicator.

4. An apparatus as set forth in claim 1, wherein the stack device (66) is arranged above the base (1) of the apparatus and withdrawing means (68) are provided at the inner end of the stack device (66) for receiving receptor material, the said withdrawing means are mounted between the stack device and a U-shaped curved guide member (70) which guides the sheet of receptor material to the picture transfer device (40), the latter containing a cylinder (41) and contact pressure rollers (42, 43) running on the periphery of the said cylinder (41), wherein further the receptor material is guided, on the side of the picture transfer device (40) remote from the stack device (66), between the cylinder (41) and the contact pressure roller (43) and the laminate formed by the receptor material and the recording carrier is removed on a side facing the stack device from the cylinder (41) behind a further contact pressure roller (42), and a removal device (55, 99, 100) is arranged on a partition (50) behind the picture transfer device and collaborates with the recording carrier and detaches the receptor material therefrom after the transfer of the picture.

5. An apparatus as set forth in claim 4, wherein the removal arrangement contains a deflecting device (99, 100) which deflects the recording carriers within its guide at a small radius of curvature away from the receptor material, wherein the deflecting roller is a roller (99) with small diameter.

6. An apparatus as set forth in claim 1, comprising a burner chamber (77) below the exposure aperture (5) and the associated part (24, 25, 26) of the exposure device, said burner chamber being defined on one hand by a side wall (4) and on the other hand by a partitioning device (49) for forming the chamber for the recording carrier, wherein heat sources (75, 76) are arranged in this burner chamber (77), the lower part of the burner cham-

ber, under the said heat sources, is closed by a guide partition (72), extending from the picture transfer device (40) to a delivery aperture (71) in the side wall, wherein furthermore a fan (78) is located in the said burner chamber for removing excess heat above the heat sources (75, 76) and from the zone of the exposure light sources (24, 25) arranged in the zone of the exposure slot (5).

5 7. An apparatus as set forth in claim 1, wherein the chamber, formed by the partitions (31, 49, 50, 51) and 10 adapted to receive the recording carrier, is subdivided by a further partition (56), having at least one passage therein for the recording carrier (33), wherein the partial chamber formed in this manner receives the storage roller (34), the charging device (38) and the picture transfer device (41), and the other partial chamber the take-up roller (35) and the cleaning devices (45, 46).
